COMBINED TENNIS BALL RETRIEVER AND STORAGE CONTAINER

Frederick D. Heffner, San Gabriel, Calif.
(2350 Huntington Drive, San Marino, Calif. 91108)

Filed Sept. 4, 1973, Ser. No. 393,992

Term of patents 14 years

Int. Cl. D21—02

U.S. Cl. D34—5 ST

FIG. 1 is a perspective view of a combined tennis ball retriever and storage container with carrying handles folded down to form a stand;

FIG. 2 is a front elevation (the rear elevation is identical) of the device with handles folded up in operating position;

FIG. 3 is a side elevation (the side views are identical) of the device as shown in FIG. 2;

FIG. 4 is a top view of the device as shown in FIG. 3; and

FIG. 5 is a bottom view of the device as shown in FIG. 3.

I claim:

The ornamental design for a combined tennis ball retriever and storage container, substantially as shown and described.
